BLASTING CONTROL

Richard N. Snyder, 6505 Lignum St.,
Springfield, Va. 22150

Filed Jan. 13, 1971, Ser. No. 106,303

Term of patent 14 years

Int. Cl. D13—03

U.S. Cl. D26—13 C

Fig. 1

Fig. 2

FIG. 1 is a front elevational view or the like of a blasting control box embodying my new design.

FIG. 2 is an exploded perspective view. The sides not seen in FIG. 2 are similar to those shown. The front panel of the lid is planar and unornamented.

I claim:

The ornamental design for a blasting control, as shown.
